(57) CLAIM

The ornamental design for an air cooled battery charger, as shown.

DESCRIPTION

FIG. 1, is a front perspective view of an air cooled battery charger, a new design;

FIG. 2, is a front perspective view thereof;

FIG. 3, is a rear view thereof;

FIG. 4, is a left side view thereof;

FIG. 5, is a right view thereof;

FIG. 6, is a bottom view thereof; and,

FIG. 7, is a top view thereof.

The portions of the Figures shown in broken and phantom lines are for illustrative purpose only and form no part of the claimed design.
